RETURN MECHANISM

Arthur C. Hughes, Jr., Puente, Calif., assignor,
by mesne assignments, to the United States
of America as represented by the Secretary
of the Navy

Application March 14, 1946, Serial No. 654,494

11 Claims. (Cl. 267—1)

1

This invention pertains to mechanical means for returning to center from rotary displacement, and more particularly to such means which are compact in construction and simple and positive in operation.

It is sometimes desirable to equip a shaft with a device which will return the shaft to some predetermined original position after the shaft has been turned from that position and then released. One example of such an operation is found in some constructions involving potentiometers. The prior art has included means for returning to center from a rotary displacement. What is proposed here is a novel means for accomplishing this result, one which comprises a single power spring.

An object of this invention is to provide a novel device for automatically returning a shaft to a predetermined position upon rotary displacement from such predetermined position.

Another object of this invention is to provide a novel centering device for automatically returning to a predetermined center position a shaft which has been subjected to rotary motion.

Still another object of this invention is to provide a novel centering device having a single spring for automatically returning to a predetermined center position a shaft which has been subjected to rotary motion, said spring being operable irrespective of the direction of rotation of said shaft from said center position.

Other objects and advantages of this invention will be apparent from the accompanying claims and description, taken in connection with the drawings in which:

Fig. 1 is a perspective view of the device dismantled to facilitate understanding, said view showing all of the essential features except the single power spring;

Fig. 2 is a perspective view of the interior elements assembled, but does not show the case which houses those elements;

Fig. 3 is a plan view of an assembly with cap removed, and

Fig. 4 is an elevation, in section better to reveal details.

Referring to Fig. 1 there is shown a main shaft 11 with an arm 12 fixedly secured thereto. A case 13 contains a case bearing 14 which provides support for shaft 11. Arm 12 carries a centering pin 15, fixedly secured to it. A second shaft 16 has fixedly secured to it a first disc 17, shaped as shown in the drawings. Inherent in the shape of disc 17 are working surfaces 30, 31

and 32, the functions of which will be described below under the description of operation. Also fixedly secured to shaft 16 is a bushing 24, the function of which is defined below. As is shown best in Fig. 4, shaft 16 is supported at one end by a bearing 33 in such a manner that shafts 11 and 16 are concentrically and rotatably mounted with respect to each other. The other end of shaft 16 is supported by a bearing 9 mounted in a cap 8 on case 13.

Referring again to Fig. 1 there is shown a lug 18 secured to shaft 16 for anchoring one end of a spiral spring 19. Spring 19 appears in Figs. 2, 3 and 4. Also shown in Fig. 1 are a stop 20, fixedly mounted in case 13, and a second disc 21 with a pin 22 for securing the second end of spring 19. Disc 21 has a centrally-located circular opening 23 to support disc 21 on aforementioned bushing 24 of shaft 16. Inherent in the shape of disc 21 are working surfaces 34, 35, and 36, corresponding to surfaces 30, 31 and 32 of disc 17.

Operation of this invention is best understood from a study of Fig. 2. In operation centering pin 15 normally is held in its zero (or center) position by the combined restraining action of surface 34 of disc 21 and surface 30 of disc 17. These discs themselves are zero positioned by surfaces 36 and 32, of discs 21 and 17 respectively, bearing on stop 20 which is fixed with respect to case 13. Discs 17 and 21 and spring 19 are so installed that some stress exists in spring 19 when it is holding the discs in their zero position. If through application of an external force main shaft 11 is turned clockwise (as seen from the input end) disc 17 will be rotated by the action of centering pin 15 bearing on surface 30. Since one end of spring 19 is secured to lug 18 of shaft 16, which turns with disc 17, and the other end of spring 19 is secured to pin 22 on disc 21, held fixed by surface 36 bearing on stop 20, spring 19 consequently will be stressed during this operation. During the rotation, therefore, energy is stored in spring 19. This stored energy will return disc 17, and consequently centering pin 15 and shaft 11, to the zero position upon removal of the external force which caused the rotation.

If the external force applied to main shaft 11 is such as to cause rotation in a counterclockwise direction (as seen from the input end) disc 17 will remain without rotation because of surface 32 bearing on stop 20, but centering pin 15 will act against surface 34 and cause rotation of disc 21. As before, energy is stored in spring

19 during this rotary deflection, which energy will restore to the zero position disc 21, centering pin 15 and main shaft 11 upon removal of the external force.

In the figures the shape of discs 17 and 21 and the position of stop 20 with respect to the zero position of centering pin 15 are such as to limit rotation of main shaft 11 to 90 degrees either side of its zero position. It is emphasized that this is for example only, and that the maximum rotation of main shaft 11 may have any value within desirable predetermined limits without departing from the principles of this invention.

What is claimed is:

1. A centering device for returning a shaft to a predetermined center position, said device comprising a housing, a shaft rotatably mounted in said housing, an arm fixedly secured to said shaft, a second shaft rotatably mounted in said housing, a first disc fixedly mounted on said second shaft, a second disc rotatably mounted on said second shaft, means on said housing and said discs for limiting rotation of one of said discs in one direction and for limiting rotation of the other of said discs in the opposite direction, means on said arm and said first disc responsive to one direction of rotation of said arm for causing rotation of said first disc, means on said arm and said second disc responsive to the opposite direction of rotation of said arm for causing rotation of said second disc, and means operatively connecting said second-mentioned disc and said second-mentioned shaft for returning said first-mentioned shaft to a predetermined position upon displacement therefrom.

2. A centering device for returning a shaft to a predetermined center position, said device comprising a housing, a shaft rotatably mounted in said housing, an arm fixedly secured to said shaft, a second shaft rotatably mounted within said housing, a first disc fixedly mounted on said second shaft, a second disc rotatably mounted on said second shaft, means on said housing and said discs for limiting rotation of said first-mentioned disc in one direction and for limiting rotation of said second-mentioned disc in the opposite direction, a pin mounted on said arm, means on said first disc to engage said pin for causing rotation of said first-mentioned disc in response to one direction of rotation of said first shaft, means on said second disc to engage said pin for causing rotation of said second-mentioned disc in response to the opposite direction of rotation of said first shaft, and a spring operatively connecting said second-mentioned disc and said second-mentioned shaft for returning said first-mentioned shaft to a predetermined center position upon displacement of said shaft from said position.

3. A centering device for returning a shaft to a predetermined center position, said device comprising a housing, a shaft rotatably mounted in said housing, an arm fixedly secured to said shaft, a second shaft rotatably mounted within said housing, a first disc fixedly mounted on said second shaft, a second disc rotatably mounted on said second shaft, a first pin mounted on said housing and means on said first-mentioned disc for engaging said first pin for limiting rotation of said first-mentioned disc in one direction and means on said second-mentioned disc for engaging said first pin for limiting rotation of said second-mentioned disc in the opposite direction,

5 a second pin mounted on said arm and means on said first-mentioned disc for engaging said second pin for rotating said first-mentioned disc in response to one direction of rotation of said first shaft and means on said second-mentioned disc for engaging said second pin for rotating said second-mentioned disc in response to the opposite direction of rotation of said first shaft, and a spring operatively connecting said second-mentioned disc and said second-mentioned shaft for returning said first-mentioned shaft to a predetermined center position upon angular displacement of said shaft from said position.

4. A centering device for returning a shaft to a predetermined center position within a housing comprising, an arm fixedly attached to said shaft, a stop fixedly attached to said housing, a first member rotatable within said housing, disposed coaxially with said shaft and bearing upon said arm, a second member rotatable within said housing, disposed coaxially with said shaft and also bearing on said arm, a spring connected between said first and second members for urging said first member and said shaft in a clockwise direction, and for simultaneously urging said second member and said shaft in a counterclockwise direction, first means on said first and second members for engaging said stop to limit rotation of said members, second means on said first and second members for engaging said stop to determine the position of rest of said members and thereby said center position.

5. A centering device for returning a rotatable main shaft to a predetermined center position within a housing comprising, a stop fixedly attached within said housing, an arm fixedly attached to said shaft and extending radially therefrom within said housing, a first substantially disc shaped member rotatable within said housing and disposed coaxially with said shaft, an auxiliary shaft attached to said member and extending axially therefrom, a second substantially disc shaped member rotatably mounted upon said auxiliary shaft, a spiral spring mounted under stress between a point on said second disc shaped member and a point on said auxiliary shaft, said spring urging said first member in a clockwise direction and said second member in a counterclockwise direction, first surfaces on said members acting oppositely on said arm, and second surfaces on said members for engaging said stop from opposite sides.

6. A centering device for returning a shaft to a predetermined center position of rotation comprising, first and second members rotatably mounted about an axis coincident with the rotational axis of said shaft, a spring member connecting said first and second members and urging relative rotation between said first and second members, a stop fixed in position relative to said center position of said shaft, each of said first and second members being formed with at least one stop engaging means for limiting rotation of said first and second members by engagement with said stop, a third member secured to said shaft and rotatable therewith, said first member being formed with means engaging said third member upon rotation of said shaft in a first direction from said center position to cause said first member to rotate with said shaft in said first direction, said second member being formed with means engaging said third member upon rotation of said shaft in the opposite direction from said center position to cause said

second member to rotate with said shaft in said second direction.

7. A centering device for returning a shaft to a predetermined center position of rotation comprising, first and second members rotatably mounted about an axis coincident with the rotational axis of said shaft, a spring member connecting said first and second members and urging relative rotation between said first and second members, said first member being urged in a clockwise direction and said second member being urged in a counterclockwise direction, a stop fixed in position relative to said center position of said shaft, each of said first and second members being formed with a stop engaging means for limiting rotation of said first and second members in clockwise and counterclockwise directions, respectively, by engagement with said stop thereby to determine the position of rest of said first and second members, a third member secured to said shaft and rotatable therewith, said first member being formed with means engaging said third member upon rotation of said shaft in a counterclockwise direction from said center position to cause said first member to rotate with said shaft in said second direction.

8. A centering device as in claim 7 wherein said means on said first and second members engaging said third member simultaneously engage said third member when said shaft is in said center position and said first and second members are in their respective rest positions.

9. A centering device for returning a shaft to a predetermined center position of rotation and for limiting the rotation of said shaft from said center position comprising, first and second members rotatably mounted about an axis coincident with the rotational axis of said shaft, a spring member acting between said first and second members and urging relative rotation of said first and second members, said first member being urged in a clockwise direction relative to said second member, said first and second members each being formed with an arcuate way of predetermined length, a stop member fixed in position relative to said center position of said shaft and disposed in said ways of said first and second members, rotation of said first and second

members being limited by engagement of said stop member with the ends of said ways, a third member secured to said shaft and rotatable therewith, said first member being formed with means engaging said third member upon rotation of said shaft in a counterclockwise direction from said center position, said second member being formed with means engaging said third member upon rotation of said shaft in a clockwise direction from said center position.

10. A centering device for returning a shaft journaled in a housing to a predetermined center position with respect to said housing comprising, a stop fixed to said housing, a first means 15 adapted to urge the shaft in a clockwise direction relative to the housing, a second means adapted to urge the shaft in a counterclockwise direction relative to the housing, spring means acting between said first and second means and urging relative rotation of said first and second means, and means on said first and second means for engaging said stop to determine said center position.

11. A centering device for returning a shaft 25 journaled in a housing to a predetermined center position with respect to said housing comprising, an arm fixedly attached to said shaft, a stop fixedly attached to said housing, a first member adapted to bear upon said arm to urge the shaft in a clockwise direction relative to said housing, a second member adapted to bear upon said arm to urge the shaft in a counterclockwise direction relative to said housing, spring means acting between said first and second members and urging relative rotation of said first and second members, means on said first and second members for engaging said stop to limit the rotation of said members, and additional means on said first and second members for engaging said 35 stop to determine said center position.
